UNITED STATES PATENT OFFICE.

JAMES T. MAHONEY AND EBENEZER F. GRIFFITHS, OF PHILADELPHIA,
PENNSYLVANIA; SAID MAHONEY ASSIGNOR TO SAID GRIFFITHS.

PREPAYMENT GAS-METER.

SPECIFICATION forming part of Letters Patent No. 601,576, dated March 29, 1898.

Application filed June 30, 1897. Serial No. 642,954. (No model.)

To all whom it may concern:

Be it known that we, JAMES T. MAHONEY, a citizen of the United States, and EBENEZER F. GRIFFITHS, a subject of the Queen of Great Britain, (having declared his intention to become a citizen of the United States,) both residing at Philadelphia, in the county of Philadelphia and State of Pennsylvania, have invented certain new and useful Improvements in Prepayment-Movements for Gas-Meters, of which the following is a specification, reference being had therein to the accompanying drawings.

Our invention relates to prepayment-movements to be attached to gas-meters; and the object of our improvement is to provide a simple and effective device that can be used in conjunction with the ordinary form of gas-meters, the mechanism of said movement being set in motion only after a coin of particular size and value has been deposited in the coin - slot and securely and automatically locked after a predetermined volume of gas has passed through the meter. To accomplish the desired result, our invention is constructed in the manner hereinafter described, and more particularly pointed out in the claims.

In the accompanying drawings, Figure 1 is a plan view of the top of an ordinary gas-meter having our improvement therein, the top of the meter being removed. Fig. 2 is a front elevation of the meter and coin-box, showing the dial that registers the amount purchased and for which coins have been deposited. Fig. 3 is a sectional elevation on line xx of Fig. 1. Fig. 4 is an inside view of the face-plate of the coin-box, showing a part of the vending mechanism attached thereto. Fig. 5 is a sectional detail on line $x'x'$ of Fig. 3. Fig. 6 is a sectional elevation on line yy of Fig. 3, showing the passage of the coin to the operating-lever. Fig. 7 is a sectional detail on line $y'y'$ of Fig. 6. Fig. 8 is a sectional elevation through the valve-box and its connections on line $y'y'$ of Fig. 1. Figs. 9 and 10 are views of a modified form of gearing to operate the mechanism that controls the flow of gas.

50 A represents the outer casing of the gas-meter, which is of the ordinary construction.

A' is the inlet connected to the street-main, and A^2 the gas-outlet connecting to the house-pipes.

a are downwardly-cupped openings in the bottom of the valve - box. Through these openings the gas is admitted to the meter, flowing in the direction indicated by the arrows.

a' is the valve controlling the flow of gas from the inlet-pipe A' into the body of the meter. This valve is connected with and controlled by the coin-actuated mechanism.

b , b' , b^2 , and b^3 are the various levers operated by the vertical shafts b^4 and b^5 , that connect with the bellows in the gas-meter.

b^6 is a vertical crank-shaft extending to and operating the valves in the gas-meters. The levers b , b' , b^2 , and b^3 and the shafts b^4 b^5 and the crank-shaft b^6 are identical in construction with those parts of the ordinary meter and perform the same functions.

a^2 is a horizontal shaft extending from the vertical crank-shaft b^6 to and operating the usual form of dial mechanism on the front of the meter, and b^7 is the worm gear-wheel on the crank-shaft b^6 .

a^3 is a spur gear-wheel on the inner end of the shaft a^2 and engaging with the worm gear-wheel b^7 , and a^4 is a worm gear-wheel on the shaft a^2 .

c is a screw-threaded shaft having one end secured in a suitable bearing formed in the support c' , the opposite end fitting into a cylindrical opening formed in the square shaft d , that has a suitable bearing in the support c^2 .

c^3 is a spur gear-wheel on the shaft c and engaging with the worm gear-wheel a^4 on the shaft a^2 .

c^x is a lug or projection on the wheel c^3 .

d is a stuffing-box on the shaft d to prevent any gas escaping from the meter into the coin-box at this point, and d^2 is a short arm or lever on the extreme end of the shaft d .

d^3 is a hollow cylindrical rack, one end fitting over the square shaft d , the opposite end being internally screw-threaded to fit over the screw-threaded shaft c .

d^x is a lug or projection on the inner end of the hollow cylindrical rack d^3 , which lug, in conjunction with the lug c^x on the wheel

*c*³, forms a stop for the rack and prevents any jamming up against the wheel *c*³.

*d*⁴ is a shaft supported above and at right angles to the hollow cylindrical rack *d*³, and *d*⁵ is a spur gear wheel or pinion on the shaft *d*⁴ and engaging with hollow cylindrical rack *d*³.

*d*⁶ is an arm or lever secured on the shaft *d*⁴, and *d*⁷ is another but shorter arm secured on the shaft *d*⁴.

Both of these levers *d*⁶ and *d*⁷ have their free ends bent over at right angles to the main portion. The outer end of the shaft *d*⁴ projects through the center of the large prepayment-dial *A*³ (shown in Fig. 1) and is provided with a suitable pointer or hand that moves around the dial over the figures and words marked thereon.

e is a horizontal shaft having a suitable bearing in the same vertical support *e*' that holds the inner end of the shaft *d*⁴ in position, and *e*² is a curved lever on one end of the shaft *e*.

The free bent-over ends of the levers *d*⁶ and *d*⁷ slide along and over the inner edge of this curved lever *e*², whereby the said curved lever is thrown out for the purpose of causing the valve *a*' to be opened to permit the flow of gas.

*e*³ is a short arm or extension formed integral with the hub portion of the lever *e*² and is adapted to be engaged and operated by the turned-over ends of the lever *d*⁶ for the purpose of closing the valve *a*' after a predetermined quantity of gas has been passed.

*e*⁴ is a straight arm or lever secured on the inner end of the shaft *e*. Upon the free end of this arm *e*⁴ the valve *a*' is secured. The forward movement of the lever *d*⁶ will press back the curved lever *e*² and thus open the valve *a*', and the reverse movement will close said valve when the lever *d*⁶ comes in contact with the short arm or extension *e*³ in the position shown in Fig. 8. The lever *d*⁷ is made shorter than the lever *d*⁶, so that it will pass over the end of the arm or extension *e*³ without touching it. When the lever *d*⁶ has passed beyond the free end of the curved lever *e*², the lever *d*⁷ will prevent the curved lever from falling back and thus closing the valve.

B is the face-plate of the coin-box and to which the coin-actuated mechanism is secured.

50 *B*' is the coin-slot formed on the inner side of the face-plate.

*B*² is the knob or handle for starting the mechanism after the coin has been placed in the coin-slot, and *B*³ is the coin-box, into which the coins fall after passing through the coin-slot.

55 *C* is a spur gear-wheel on the inner end of the spindle that holds the knob *B*².

C' is a spur gear-wheel on a shaft located above the gear-wheel *C*.

*C*² is a spur gear-wheel on a shaft below the gear-wheel *C*, and *C*³ is an idler gear-wheel engaging with the wheels *C* and *C*'.

60 *D* is a ratchet-wheel secured on the extreme end of the spindle carrying the knob *B*².

D' is a pawl for preventing the backward

movement of the ratchet-wheel *D*, and *D*² is another pawl or catch located on the side of the ratchet-wheel opposite the pawl *D*' and adapted to drop into the rectangular notch *f* at regular predetermined intervals, thus preventing said ratchet-wheel from moving in either direction. This notch *f* is rectangular in shape and is located in the periphery of the ratchet-wheel *D*, and is as long as and occupies the place of one of the ratchet-teeth of said wheel. By reason of the length of the notch *f* the knob *B*² will be capable of a slight movement when the pawl *D*² is in engagement therewith, but not sufficient to permit the operation of the device.

f' is a spiral spring holding the two pawls *D* and *D*² up against the ratchet-wheel.

*D*³ is a connecting-rod having one end there- 85 of secured at or near the outer edge of the ratchet-wheel and the opposite end jointedly connected with the free end of the short arm or lever *D*⁴, secured on the rock-shaft *E*.

E' is a curved arm secured to the shaft *E* and having the free end thereof bent inwardly at right angles to the body of said lever, so as to form thereon a finger *g*, that presses against the edge of the coin *G*.

*E*² is a rock-shaft upon which the pawl *D*² 95 is secured, and *E*³ is a short arm or lever se- cured rigidly to the shaft *E*² and beveled in- wardly in the manner shown in Fig. 7.

*C*⁴ is a flat disk secured to the shaft that carries the spur gear-wheel *C*', and *f*² is a pin 100 secured in the disk *C*⁴, near the edge thereof. If preferred, this pin may be lengthened somewhat and placed in the wheel *C*' and the disk *C*⁴ omitted entirely.

*f*³ and *f*⁴ are pins projecting from the side 105 of the gear-wheel *C*² and acting upon the pawl *D*² to prevent it from falling into the notch *f* in the ratchet-wheel *D* except at regular pre- determined intervals.

g' is a channel or raceway formed on the 110 inside of the face-plate *B* at or near the bot- tom of the coin-slot *B*'. In this channel the coin-finger *g* on the curved arm *E*' moves back and forward, pressing against the upper edge of the coin *G*, and thus forcing it 115 out and into the coin-box *B*³, located directly under the coin-slot.

The prepayment-movement being con- 120 structed as shown and connected to the gas- meter in the manner herein described, with the inlet-pipe *A*' connected to a gas-main and the outlet *A*² to the house gas-pipes, the op- eration is as follows: The coin is placed in the opening at the top of the coin-slot *B*' (shown in Fig. 1) and will fall into the position 125 shown in Figs. 4 and 6. The knob *B*² is then turned to the right or toward the front of the meter. This movement, owing to the length of the notch *f* and the play of the pawl *D*² therein, turns the ratchet-wheel *D*, forcing down the 130 long connecting-rod *D*³, carrying with it the short arm or lever *D*⁴, turning the shaft *E*, and consequently the curved lever *E*'. This will bring the finger *g* against the rear edge

of the coin G, pushing it out into the coin-box B³. As the coin passes or is forced out it impinges against the beveled edge of the arm or lever E³, forcing said arm downward 5 and turning the shaft E² and raising the pawl or catch D² out of the notch f in the ratchet-wheel, thus allowing said wheel to turn freely. The knob B² is turned until it will go no farther, being stopped by the pawl D² falling 10 again into the notch f. The turning of the knob B² will, acting through the cog-wheels C, C³, and C', turn the flat disk C⁴, when the pin f² will engage with the short lever d² on the end of the square shaft d, causing said 15 shaft to turn, carrying with it the hollow cylindrical rack d³. As this cylindrical rack d³ moves forward on the screw-shaft c the pinion d⁵ is turned, thus operating the shaft d⁴ and moving the levers d⁶ and d⁷, causing the 20 lever d⁸ to come in contact with the curved arm e², which, being secured to the shaft e, causes it to turn partially around and raise the straight arm or lever e⁴ and open the valve a', thus allowing the gas to enter into and 25 pass through the meter, going from thence through the outlet-pipe A' to the house-pipes in the regular way. The flow of gas being once started it will continue until by the reverse movement of the mechanism the valve 30 a' is closed. The closing operation is as follows: The vertical crank-shaft b⁶, being turned by the flow of gas in the regular way, operates the shaft h². This will turn the worm gear-wheel a⁴, causing it turn the spur gear-wheel c³ and operate the screw-shaft c, which as it turns will cause the cylindrical rack d³ to move from right to left, turning the pinion d⁵ and revolving the shaft d⁴, causing the arm d⁶ to move along the inner edge of the curved 35 lever e² and impinge against the short extension e³, causing the shaft e to turn and operate the valve-arm e⁴, thus closing the valve a' and shutting off the supply of gas.

The coin-box B³ is closed on all sides and 40 provided with a suitable door through which the coins may be removed. The coin-actuated mechanism attached to the face-plate B is also securely closed in, so that it can at no time be tampered with. The valve a' is surrounded with a suitable gas-tight box, so as 45 to keep the gas from the other parts of the device.

The downwardly-cupped gas-admission openings a a in the bottom of the valve-box 50 prevent any meddling with the valve a' by means of a wire or other device passed down the inlet-pipe A'.

In place of the spur gear-wheel C² (shown 55 in Figs. 3 and 4) the intermittent star-wheel C⁵ (shown in Figs. 9 and 10) may be used, in which case it will be necessary to place the single-tooth trip-wheel C⁶ on the knob-spindle between the cog-wheel C and the ratchet-wheel D.

60 Instead of the shaft d being squared, as shown, it may be of any desired shape that will

permit the rack d³ to slide to and fro thereon, yet prevent it rotating independently thereof.

The one side of the coin passage or raceway g' and the inner side of the arm or lever E² 70 being beveled, as shown in Fig. 7, a thin or small coin will pass through without operating the unlocking mechanism.

The mechanism shown and described is adapted to the sale of gas at the rate of one 75 dollar and twenty-five cents per thousand feet, a quarter of a dollar being placed in the coin-box for every two hundred feet purchased and the knob B² given five full revolutions. When the coin-actuating mechanism is in the position shown in Fig. 4, the free end of the pawl D² will be in the rectangular notch f and not in contact with either of the pins f³ and f⁴. After the coin has been dropped into the slot B' the turning of the 80 knob B² will give the ratchet-wheel D a slight movement, which will depress the levers D³ and D⁴, rock the shaft E, and consequently the lever E', secured thereon, and bring the finger g thereof in contact with the top of the coin 85 G, pressing said coin G down, and consequently the lever E³ upon which it rests, which will rock the shaft E² and thus will raise the pawl D² out of said notch f and allow the ratchet-wheel to turn. The cog-wheels C and 90 C² are so proportioned relatively that at every revolution of the wheel C the wheel C² will make four-fifths of a revolution, bringing the pins f³ and f⁴ in such position that one or the other of them will hold the pawl D² out of the 95 rectangular notch f in the ratchet-wheel D. The same conditions will exist at the second, third, and fourth revolutions; but at the end of the fifth revolution the pins f³ and f⁴ will be at the starting-point and in such position 100 that the pawl D² will fall into the notch f. After putting a quarter of a dollar in the coin-slot five revolutions of the knob B² will turn all of the mechanism, so that the hand on the prepayment-dial A³ will go forward from "0" 105 to the "200" mark. If another quarter is placed in the coin-slot and the knob again given five revolutions, the hand on the prepayment-dial will point to "400," and so on until five quarters have been placed in the coin-box, when the pointer on the dial will be at the "1000" mark. When the hand on the dial indicates one thousand, the knob B² has 110 been turned to the right as far as it can possibly go, as the lug d* on the rack d³ will engage the lug c* on the wheel c³, so that the dropping of additional coins in the slot will be of no avail to operate the machine until some of the gas has been consumed. Instead 115 of having the dial register one thousand it may register any desired amount and the different parts proportioned accordingly.

Should the price of gas be more or less than one dollar and twenty-five cents per thousand feet, the relative proportions of the various 120 parts of the vending device should be changed accordingly.

Having thus described our invention, what we claim, and desire to secure by Letters Patent, is—

1. In a prepayment gas-meter, the combination of a coin unlocking mechanism, with a non-cylindrical rotatable shaft, a hollow cylindrical and internally-screw-threaded rack having a sliding fit over the non-cylindrical shaft, a screw-threaded shaft fitting into the internally-screw-threaded portion of the cylindrical rack and connected by suitable mechanism to a shaft that is operated by the flow of gas through the meter, and a pinion mounted upon a shaft and connected with mechanism that will open or close the gas-inlet valve, as the pinion is revolved one way or the other by the lateral movement of the cylindrical rack, substantially as shown and described.
2. In a prepayment gas-meter, a non-cylindrical rotatable shaft; a cylindrical rack fitting over the non-cylindrical shaft and engaging with a pinion on a shaft that controls the gas-inlet valve; a screw-threaded shaft fitting into the cylindrical rack and operated by the flow of gas through the meter, in combination with suitable mechanism for revolving the non-cylindrical shaft, substantially as shown and described.
3. In a coin-operated gas-meter, the shaft d , operated by suitable coin-controlled mechanism, in combination with the hollow cylindrical rack d^3 , having a sliding fit over the shaft d , and internally screw-threaded at the forward end; the shaft d^4 , carrying pinion d^5 , and lever d^6 ; the shaft e , having on one end thereof the long curved lever e^2 , and the arm e^3 , and on the opposite end the lever e^4 , carrying a gas-admission valve a' ; the screw-shaft c , fitting into the internally-screw-threaded forward end of the cylindrical rack d^3 , and having thereon the spur gear-wheel c^3 , and the shaft a^2 , operated by the flow of gas through the meter and having thereon the worm gear-wheel a^4 , substantially as and for the purpose described.
4. In a prepayment coin-operated gas-meter, the combination of the shaft d , operated by the coin-controlled mechanism, the hollow cylindrical rack d^3 , internally screw-threaded at the forward end and having a sliding non-rotatable fit over the shaft d ; the shaft d^4 , having thereon the pinion d^5 , and levers d^6 , and d^7 ; the shaft e , having thereon the long curved lever e^2 , the short arm e^3 , and the lever e^4 , carrying the valve a' ; the screw-shaft c , fitting into the screw-threaded end of cylindrical rack d^3 , and into the inner end of the square shaft d ; the spur gear-wheel c^3 , on the end of the shaft c , and the worm gear-wheel a^4 , on the shaft a^2 , that is operated by the flow of gas through the meter, all arranged, substantially as shown.
5. In a prepayment coin-operated gas-meter, the combination of the shaft d , operated by a suitable coin-controlled movement, the

hollow cylindrical rack d^3 , internally screw-threaded at the forward end and the rear end fitting over the shaft d , in such a manner that it will have a sliding fit thereon but will rotate only when said shaft is turned; the shaft d^4 , having thereon the pinion d^5 , lever d^6 , and on the outer end a suitable dial pointer or hand; the prepayment-dial A^3 , having marked thereon figures that indicate the amount of gas purchased; the shaft e , having thereon the curved lever e^2 , the short arm e^3 , and the lever e^4 , carrying the valve a' ; the screw-shaft c , fitting into the cylindrical rack d^3 , and having thereon the spur gear-wheel c^3 , and the shaft a^2 , having thereon the worm gear-wheel a^4 , and operated by the flow of gas through the meter, all arranged substantially as shown and for the purpose described.

6. In a prepayment gas-meter, the coin unlocking mechanism, consisting of the plate B , having therein a coin-slot; the knob or handle B^2 , on the outer end of a spindle or shaft secured on the plate B ; the ratchet-wheel D , on the inner end of the knob-spindle; the pawls D' and D^2 , operating upon said ratchet-wheel from opposite sides thereof; the wheel C^2 , operated by a wheel on the knob-spindle and having therein the projecting pins f^3 , and f^4 , that operate upon the pawl D^2 , to hold it out of contact with and prevent it locking the ratchet-wheel D , except at regular intervals, the connecting-rod D^3 , jointedly connected at one end to the ratchet-wheel and at the opposite end to the arm D , secured to the shaft E , carrying coin-lever E' ; the short arm E^3 , secured rigidly to the shaft E^2 , to which the pawl D^2 , is pivoted, in combination with suitable mechanism for rotating the shaft that controls the delivery of the gas, substantially as shown and described.

7. In a prepayment gas-meter, the coin unlocking mechanism, consisting of the plate B , having therein a coin-slot; the knob or handle B^2 , on the outer end of a spindle or shaft extending through the plate B ; the ratchet-wheel D , on the inner end of the knob-spindle; the pawls D' and D^2 , operating upon said ratchet-wheel in opposite directions; the wheel C^2 , operated by a wheel on the knob-spindle and having therein projecting pins that operate upon the pawl D^2 , to hold it out of contact with the ratchet-wheel except at regular intervals; the connecting-rod D^3 , connected at one end to the ratchet-wheel and at the opposite end to the arm D^4 , secured upon the shaft E , carrying the coin-lever E' ; the short arm E^3 , secured on the shaft E^2 , that carries that pawl D^2 , in combination with the crank-arm on the end of the rotatable shaft that controls the delivery of the gas, all arranged substantially as shown.

8. In a prepayment gas-meter the combination of a coin unlocking mechanism, with a rotatable shaft, a hollow cylindrical and internally-screw-threaded rack having a sliding fit over the shaft, and means whereby said

shaft and rack will revolve together, a screw-threaded shaft fitting into the internally-screw-threaded portion of the cylindrical rack and connected by suitable mechanism to a shaft that is operated by the flow of gas through the meter, and a pinion mounted upon a shaft and connected with mechanism that will open or close the gas-inlet valve as the pinion is revolved one way or the other

by the lateral movement of the cylindrical rack, substantially as shown.

In testimony whereof we affix our signatures in presence of two witnesses.

JAMES T. MAHONEY.
